(57) **CLAIM**

We claim the ornamental design for a sponge scraper, as shown and described.

DESCRIPTION

FIG. 1 is a front, right, top perspective view of a sponge scraper, showing our new design;

FIG. 2 is a front elevation view thereof;

FIG. 3 is a rear elevation view thereof;

FIG. 4 is right elevation view thereof;

FIG. 5 is a left elevation view thereof;

FIG. 6 is a top plan view thereof; and,

FIG. 7 is a bottom plan view thereof.

The dotted pattern surface shading represents a mesh or scouring pad surface and the circular surface shading represents a sponge surface.
